UNITED STATES PATENT OFFICE.

CHARLES J. KLEIN, OF MILWAUKEE, WISCONSIN.

LAMP-SOCKET.

1,151,800.

Specification of Letters Patent. Patented Aug. 31, 1915.

Application filed January 28, 1914. Serial No. 815,048.

To all whom it may concern:

Be it known that I, CHARLES J. KLEIN, a citizen of the United States, residing at Milwaukee, in the county of Milwaukee and State of Wisconsin, have invented new and useful Improvements in Lamp-Sockets, of which the following is a full, clear, concise, and exact description, reference being had to the accompanying drawing, forming a part of this specification:

This invention relates to lamp sockets and similar devices.

This application is a continuation of my co-pending application filed Sept. 25, 1911, Serial No. 651,224 as to all the common subject-matter of the two applications.

One of the objects of the invention is to provide a lamp socket comprising few parts which may be cheaply manufactured and readily assembled.

Another object is to provide a lamp socket comprising a molded insulating casing having a snap switch mechanism and a lamp shell inclosed therein.

A further object is to provide improved means for attaching such sockets to fixtures of conventional type.

In order to more clearly disclose my invention I have illustrated a preferred embodiment thereof in the accompanying drawing, wherein,

Figure 1 is a side view of a lamp socket; Fig. 2 is an elevation of one section of the socket with the switch mechanism mounted thereon; Fig. 3 is an elevation of the other section of the socket; Fig. 4 is a sectional view of the socket at right angles to Fig. 1; Fig. 5 is a bottom view and, Fig. 6 is a perspective view of a socket bushing.

Referring more particularly to the drawing, the lamp socket shown is of porcelain or other suitable insulating material and is longitudinally and centrally divided into two semi-cylindrical sections 1 and 2. These sections are designed to fit closely together and are suitably recessed to house a switch mechanism and the current-carrying parts of the socket.

The flat faces of the two parts of the socket are provided with recesses 3 at one end, central recesses 4 and additional semi-cylindrical recesses 5 at its opposite end whereby when the parts are joined these recesses respectively form a conductor entrance, a substantially closed central chamber for the switch mechanism and an open

recess at the lower end of the socket to receive a screw shell for a lamp or other device.

In the preferred form the switch mechanism and all the current-carrying parts of the socket are fixed to one section of the base. The casing may be suitably designed to receive any desired type of switch. That illustrated is of the form described and claimed in my co-pending application, filed April 28, 1911, Serial No. 623,903, and comprises a reciprocable operating member 6 arranged to oscillate a pivoted contactor 7 to make or break circuit with a snap action upon movement in opposite directions. The contactor 7 is pivoted upon a spindle 8 which also supports the operating member 6. The switch mechanism is mounted upon the section 1 of the casing and is preferably secured thereto by a supporting lug 9 fixed to the spindle 8 and firmly seated in the central recess 4 by a screw 10 or other suitable means. At diagonally opposite sides of the recess 4 a pair of stationary contacts 11 and 12 are secured to the casing by means of suitable screws. A bent terminal lug 13 leads from the contact 11 through a passage 14 to a point adjacent the conductor opening in the casing. Connected to the other contact 12 and preferably secured to the base by the same screw is a depending contact 15 passing through a recess 16 and having a bent extremity 17 constituting a center contact for the lamp.

A screw shell 18 is designed to snugly fit within the open lower recess of the lamp socket and is supported therein on one side by means of a transverse ledge 19 of the casing fitting within a cutaway portion 20 of the shell and on the other side by means of a terminal 21 preferably riveted at its lower end to the shell and leading vertically to a position adjacent the conductor entrance 3 where it is attached to the casing by a screw 22. The two terminals are provided with binding screws which work in suitable recesses in the base. The other part of the socket is provided with recesses 23 and 24 at opposite sides of the conductor entrance for receiving the terminals on the part 1 of the socket. From the recess 23 a channel 23^a leads downwardly to the bottom chamber of the socket and receives therein the terminal 21 when the sections are united. The central recess 4 in this part of the casing is provided with a well 25 within

which fits the free end of the spindle 8 of the switch mechanism. A transverse recess 26 extends across the adjacent faces of the socket parts for accommodating the switch operating member 6.

Complementary projections 27 and 28 are provided in the closed end of the lower recess of the socket. These projections, when the parts are joined, fit through a cutaway portion 29 in the screw shell and serve to prevent any accidental short-circuiting between the central contact 17 and the upper flange of the screw shell, and also serve to hold the shell against rotary movement. The two parts of the socket are preferably secured together by means of a screw 30 passing through registering openings in the base projections 27, 28 above described, and received in a nut 31. When a lamp is inserted in the socket, and the switch closed, circuit may be traced from the terminal 13 across the switch to terminal 17, through the lamp, and by shell 18 and terminal 21 to the return conductor.

In order to adapt the socket for use with fixtures of the conventional type, I provide a metal bushing 32 within the conductor entrance of the casing. As shown, this bushing comprises an interiorly threaded nozzle 33 having depending tongues 34 and 35 on opposite sides. The tongue 34 is preferably substantially rectangular and is secured to the part 1 of the socket by means of two screws passing through a metal connecting link 36 countersunk in a recess on the exterior of the casing. The other tongue 35 is preferably arranged to receive a single screw extending through the other section of the casing.

Attachment of the socket to a fixture is accomplished readily and without danger to the frangible casing by first attaching the section 1 of the socket which carries the switch parts and thereafter fastening the other section of the socket thereto. In this manner the opposite tongues 34 and 35 of the bushing provide stops or fulcrums between which a screw driver or any suitable tool may be inserted and the bushing screwed upon the fixture nipple without strain upon the casing. The tongue 35 may be provided with recesses 37 on its sides so that accidental slippage of the operating tool is prevented while the socket is being attached to the fixture.

The socket described is of sturdy and substantial construction comprising a small number of parts which may be very cheaply manufactured. Furthermore, the device may be finished as desired to harmonize with all styles of fixtures. The switch mechanism is securely mounted and all conducting parts are thoroughly insulated from each other and from the exterior of the casing. Furthermore, the switch mechanism and

conducting parts are attached directly to the socket casing in recesses which are molded in the casing when made. The several interfitting projections and recesses of the socket parts, in addition to their constituting effective insulation walls, also serve to interlock the parts and minimize the strain upon the screw connecting the sections.

What I claim as new and desire to secure by Letters Patent is:

1. A lamp socket comprising, in combination, a longitudinally divided casing of molded insulation having complementary recesses in the adjacent faces of its parts forming a conductor opening at one end and a lamp receiving recess at the other end and an intermediate substantially closed chamber, a snap switch mechanism within said chamber, a conducting shell within said lamp receiving recess and binding posts within said conductor opening, said mechanism, said shell and said binding posts being mounted on one part of said casing, and the other part of the casing being detachable to expose said current carrying elements. 75

2. In combination, a longitudinally divided insulating casing having a conductor opening at one end and a central chamber and a lamp-receiving recess at the other end, a switch mechanism mounted within said central chamber and having one terminal extending adjacent said conductor opening and a second terminal extending within said lamp-receiving recess and constituting a center contact therein, and a threaded conducting shell mounted within said lamp-receiving recess and having a terminal extending adjacent said conductor opening at a point removed from said first-mentioned terminal. 95

3. In combination, a molded insulating casing comprising two substantially semi-cylindrical sections, the adjacent faces of said sections being provided with a plurality of complementary recesses, a switch mechanism mounted within one of said recesses, a threaded conducting shell mounted within another of said recesses, terminals for said switch mechanism and said conducting shell extending adjacent a third of said recesses, and means for securing said sections together. 110

4. In combination, a longitudinally divided two-part insulating casing having a conductor opening at one end and a substantially closed central chamber and a lamp-receiving recess at the other end, a switch mechanism mounted in said chamber and a conducting shell mounted in said lamp-receiving recess, the parts of said casing having complementary projections interfitting within recesses in said shell for supporting the latter and for holding the same against rotation. 120 125 130

5. In combination, a longitudinally divided insulating casing having complementary recesses on its adjacent faces forming a conductor opening and a central chamber and a lamp-receiving recess when the sections are joined, a switch mechanism carried between the parts of said casing within said chamber, said switch mechanism having a terminal extending within said lamp-receiving chamber and constituting a center contact therein, a threaded conducting shell mounted within said lamp receiving chamber and having cutaway portions, the sections of said casing having complementary projections interfitting within said cutaway portions of said shell to hold the latter against rotation and to insulate said center contact from said shell.
6. A longitudinally divided two-part insulating casing having a conductor opening at one end and a metallic bushing fixed to one section of said casing within said conductor opening and having a pair of oppositely disposed portions adapted to receive an operating tool for rotation of the bushing.
7. In combination, a sectional socket casing of molded insulation and a metal bushing carried thereby for attaching the same to a support, said bushing having strain receiving means for enabling its rotation by direct exertion thereon, and said casing having a section detachable to expose said means.
8. In combination, a sectional socket casing of molded insulation and a strain receiving bushing carried thereby for attaching the same to a support, said casing having a section detachable to render said bushing accessible from the side for manipulation.
9. In combination, a sectional socket casing of molded insulation, a metal bushing carried thereby for attaching the same to a support, said bushing having a forked portion to receive an operating tool, and means for detachably securing one of the sections of said casing to said bushing, said section being detachable from the other section to render said forked portion of said bushing accessible to receive the operating tool.

In witness whereof, I have hereunto subscribed my name in the presence of two witnesses.

CHARLES J. KLEIN.
